UNITED STATES PATENT OFFICE

159,102

COMBINED TIME-CONTROLLED RADIO AND NIGHT LIGHT

Emmett A. Schwartz and Milton E. Anderson,
Compton, Calif.

Application July 19, 1948, Serial No. 147,656

Term of patent 3½ years

(Cl. D56—4)

To all whom it may concern:

Be it known that we, Emmett A. Schwartz and Milton E. Anderson, citizens of the United States, residing in Compton, in the county of Los Angeles and State of California, have invented a new, original, and ornamental Design for a Combined Time-Controlled Radio and Night Light, of which the following is a specification, reference being had to the accompanying drawing, forming part thereof.

Fig. 1 is a front elevational view of a combined time-controlled radio and night light, showing our new design.

Fig. 2 is a top plan view thereof.

Fig. 3 is a fragmentary front elevational view, showing the door concealing the night lamp at the left in open condition.

The characteristic features of our design re-

side in the portions shown by means of full lines in the drawing.

We claim:

The ornamental design for a combined time-controlled radio and night light, substantially as shown and described.

EMMETT A. SCHWARTZ.
MILTON E. ANDERSON.
